FRED TOLBERT, OF FORT SMITH, ARKANSAS, ASSIGNOR OF ONE-HALF TO HORACE W. COLLIER, OF FORT SMITH, ARKANSAS.

RAILWAY-SWITCH.

1,097,065.

Specification of Letters Patent.

Patented May 19, 1914.

Application filed July 15, 1912. Serial No. 709,378.

To all whom it may concern:

Be it known that I, FRED TOLBERT, a citizen of the United States, and a resident of Fort Smith, county of Sebastian, and State 5 of Arkansas, have invented a certain useful Railway-Switch; and I do hereby declare that the following is a full, clear, and exact description thereof, reference being had to the accompanying drawings.

10 The object of this invention is to provide an improved construction in railways for enabling a switch to be thrown by some means on a passing car.

The chief feature of the invention consists in the combination with a switch of a double spring for resisting its movement in either direction, means for throwing the switch having a cam or wedge-shape portion, and a locking means or plug actuated 20 by a spring or gravity for locking the switch throwing means in its two positions and against the action of the springs of the switch.

The nature of the invention will be understood from the accompanying drawings and the following description and claims:

In the drawings, Figure 1 is a plan view of a section of railway at a switch. Fig. 2 is a plan view of the switch throwing or holding mechanism with parts removed and parts broken away. Fig. 3 is a vertical section on the line 3—3 of Fig. 2. Fig. 4 is a vertical section on the line 4—4 of Fig. 3. Fig. 5 is a vertical section on the line 5—5 of Fig. 2. Fig. 6 is a plan view of a portion of the switch and the double springs for holding it, parts being broken away.

The drawings herein show in detail, a railway having cross ties 10, main track 40 rails 11 and switching rails 12 and 13 leading from one main track rail 11 at an angle therefrom. A rail 14 is pivoted to one main track rail 11 and is movable for deflecting the car wheels in the usual way. 15 25 is a guard rail.

A switch throwing rod 20 is located in a box 21 in the bed of the railway and it extends longitudinally thereof, said rod passing transversely through a hole in the switch point 14 and having a spring 22 around the rod and on each side of the switch and held in place by nuts 23 on said rod 20, so that as the rod is shifted longitudinally of its length, it will act through one or the other 50 55 of said springs to throw the switch and will

yieldingly hold the switch when thrown. One end of the rod 20 is connected with a crank 25 which is secured on the end of a shaft 26 passing through a bearing 27 in one end of the casing 21 and having bearings at 60 the other end in a casing 28 located some distance in advance of the switch. The shaft 26 is actuated by an upwardly extending crank arm 30 projecting through the top of the box or casing 28 in position to be 65 engaged or thrown one way or the other by means on a car, not shown. The shaft 26 also has bearings 31 projecting down from the top of the box 28, see Fig. 3. Hence, when the crank arm 30 is thrown to 70 one limit of its movement, it will open the switch and when thrown to the other limit of its movement, it will close the switch.

An automatically releasable stop or holding means is provided for holding the shaft 75 26 and, therefore, the switch throwing means in either of its two actuated positions and yet not interfere with the operation and throw of the crank arm 30 by means of a car. This locking or holding means is 80 shown in Fig. 4, and consists of an upwardly tapering projection 35 from the shaft 26 in position to be engaged by the lower beveled end of a stop block or bolt 36 operating vertically in a casing 37 secured to the top of the box 20. The upper end of the locking block 36 is widened or shouldered so that it cannot escape from the casing 37 because of the contracted opening 85 in the lower end of said casing 27 through 90 which the block 36 projects. This block 36 will move downward by gravity into locking position so as to engage either one side or the other of the projection 35 on the shaft and hold said shaft from any movement not 95 caused by forcible actuation of the crank arm 30. In order to make the action of the locking block, however, more positive than the result from gravity alone, a spiral spring 100 38 is located in said casing 37 in position to press down on said locking block. The upper end of the spring 38 is held down by a movable plate 39 which closes the upper end of the casing 37 and renders the same accessible. Therefore, when the crank arm 30 is thrown to its left-hand limit of movement, as shown in Fig. 4, the beveled surfaces of the parts 35 and 36 will cause the block 36 to be pushed upwardly until the shaft is actuated and then it will drop down 105

110

2 by gravity and the spring action. If the crank arm be thrown to the right, the projection 35 again would push up the locking block 36 and when the shaft 26 was thrown 5 to its other position, the locking block 36 would again move downward into locking position and hold the shaft 26 in one or the other of its actuated positions against the action of the springs 22. Therefore, the 10 springs 22 coöperate with the shaft 26, the projection 35 holding the block 36 and other parts to make the device operate. The roller 40 on the upper end of the crank arm 30 tends to reduce the friction with the switch 15 throwing mechanism on the car. The crank arms 25 and 30 are in the form of solid wrenches which slip over squared portions on the shaft 26 and are held in place by nuts, as shown in Fig. 3.

20 While the springs 22 are shown herein for yieldingly actuating the switch point, still the invention is not necessarily limited to such arrangement of springs, as any arrangement of the means for transmitting 25 power from the crank arm 30 to the switch point which is capable of yielding to some extent, meets the requirements of the invention, although the arrangement of the spring shown is a desirable one.

30 I claim as my invention:

1. A switch throwing mechanism including a rod extending loosely through the switch, a yielding means mounted on said

rod on each side of said switch and in position to yieldingly throw said switch when 35 the rod is moved in one direction or the other, a shaft for actuating said rod which has a tapering projection on the upper side thereof, a casing above said projection, a locking block vertically movable in said 40 casing with the small end tapered so as to engage either side of the projection from said shaft as it is oscillated, and means for actuating the shaft.

2. A railway switch throwing mechanism 45 including an oscillatory shaft mounted in a railway and having a tapering projection extending radially therefrom, a fixed casing with an opening in it, a locking block in said casing and projecting through said 50 opening with a tapering end adapted to engage the opposite sides of said projection from the shaft alternately as the shaft is oscillated, a spring in said casing tending to force said locking block toward the shaft, 55 means for oscillating the shaft, and yielding means for transmitting power from said shaft to the switch for throwing it.

In witness whereof, I have hereunto affixed my signature in the presence of the 60 witnesses herein named.

FRED TOLBERT.
